UNITED STATES PATENT OFFICE.

LOUIS PEROTTI, OF NEWARK, NEW JERSEY.

REFRIGERATOR.

SPECIFICATION forming part of Letters Patent No. 774,450, dated November 8, 1904.

Application filed March 15, 1904. Serial No. 198,266. (No model.)

To all whom it may concern:

Be it known that I, LOUIS PEROTTI, a subject of the King of Italy, residing at Newark, in the county of Essex and State of New Jersey, have 5 invented certain new and useful Improvements in Refrigerators; and I do hereby declare the following to be a full, clear, and exact description of the invention, such as will enable others skilled in the art to which it appertains, to make 10 and use the same, reference being had to the accompanying drawings, and to figures of reference marked thereon, which form a part of this specification.

This invention relates to that class of refrigerators represented by the one shown in my prior patent, No. 746,739, issued December 15, 1903; and the objects of this invention are to provide a household-refrigerator into which the ice can be easily inserted or supplied at 15 the bottom of the refrigerator and to allow of it to be automatically raised to the top upon closing the front door of the refrigerator, thus avoiding the necessity of lifting the ice cake by hand, and to secure a construction by which 20 the contents of the refrigerator can be reached 25 from either the front or sides thereof.

The invention also relates to some other improvements which may be referred to herein-after in connection with the description of the 30 working parts.

Referring to the accompanying drawings, in which like numerals of reference indicate corresponding parts in each of the several figures, Figure 1 shows a front view of my refrigerator; Fig. 2, a top view thereof with the top cover removed. Fig. 2^a is an enlarged detailed view of the roll applied to the front door of the refrigerator. Fig. 3 is a vertical section of same through line $x-x$ of Fig. 2. Fig. 4 is 35 a vertical section of same through line $y-y$ of Fig. 2. Fig. 4^a is a vertical section through line $x'-x'$ in Fig. 4, and Fig. 5 is a vertical section through line $z-z$ of Fig. 2.

In the drawings, number 2 indicates the 40 body of the refrigerator, and 3 the usual lower front door, providing access to the food-compartment 4. Above said food-compartment are the bottle-compartments described in my prior patent, No. 746,739. In the food-compartment two drawers 5, each having shelves 45

76, are provided and adapted to be moved in and out. When the drawers are in their normal position within the food-compartment, their inner walls 33 are located adjacent to each other, leaving a free space 9 between them for the purpose to be hereinafter described. To enable an easy movement of the drawers, the latter may be provided on their bottom with rolls 11, running upon the bottom 10 of the refrigerator. The side walls 12 60 of the shelves are shorter than the inner and outer walls thereof, so that when the drawers are withdrawn the food contained therein can be examined or removed from the sides of the drawers or some fresh food can be placed 65 therein. The bottle-compartments 13 13, located one at each end of the refrigerator above the food-compartment, have partitions 14 standing a little away from the end walls of the refrigerator and extending to a certain 70 height upward from the floors 15, cut away between the end walls of the refrigerator and the said partitions, whereby the warm air rising within the food-compartment is allowed to pass and mix with the cold air of the bottle-compartments. The inner walls 16 of these 75 compartments 13 are perforated for the passage of the cold air from the ice-compartment 17, arranged between the two bottle-compartments 13. Said inner walls 16 are removable 80 and shiftable, so that the bottle-compartments 13, according to the requirements, can be made larger or smaller. For this purpose the bottom edges of these walls 16 are provided with dovetail projections 18, one on each end, and 85 corresponding grooves 19 are crosswise or transversely arranged in the floors 15, said grooves being adapted to receive the projections 18 and to serve as guides for the walls 16. The bottle-compartments are equipped 90 with front doors 1 to allow an easy access thereto. The ice-chamber 17 consists of a suspension-floor 20, adapted to be lowered and raised. Said floor has a hole 21, over which a corrugated plate 43 may be placed to 95 support a cake of ice when put in the refrigerator. This floor 20 is held in position between the two floors 15 of the bottle-compartments by means of a counterweight 25, suspended from a chain 26. Two rails or bars 100

27 are fixed to the bottom surface of the floor 20 and are bent upward at their inner ends. A cross-piece or traverse 28 is attached to the top ends of the angular rails and has at its 5 center an upward projection or a hook 29 engaging the chain 26. Said chain is guided over a roll 30, arranged upon the back wall 31 of the refrigerator. In order to cover up the weight 25, the back wall 31 of the refrigerator may be arranged as a double wall, with a space 43 between the two parts, as shown 10 in Figs. 2 and 5. The inner part of this double wall 31 supports the guide-roll 30. In order to guide the floor 20 at its upward and 15 downward movement, the following arrangement is provided: The top part 32 of the front wall of the refrigerator is made a little thicker than the rest of it and is provided with cylindrical bores 34. To the front part 20 of the floor, on each end thereof, a tube 35 is fixed, fitting in a tube 36, which tube 36 is guided in the cylindrical bore 34 of the wall 32. These tubes thus telescope in each other and the bores, there being suitable means to 25 prevent their coming out from one another. It will be seen that when the floor 20 is lowered the tubes 35 will move outward from the tubes 36 and the latter from the bores 34, while on the other side the counterweight 30 will rise until the floor has reached the bottom of the refrigerator. When the floor is raised, the tubes will be telescopically shifted into each other and finally adopt the position shown in Fig. 3, in which the floor 20 is at 35 the same level as the floors 15 of the bottle-compartments. In order to allow of the floor 20 to be lowered and raised simultaneously with the opening and closing of the front door 3 of the refrigerator, a chain 37 is attached 40 to the bottom surface thereof, extending downward to the floor 11 of the refrigerator, where the same is guided over rolls 38 and 39 and is attached to the lower and front end of the door. There may be also a roll 40 pro- 45 vided at this part of the door, to which the front end of the chain 37 is attached and upon which the chain may be adapted to wind up and off. This roll 40 may be made under the action of a spring 41 to always turn in a 50 certain direction, and a button 42, projecting from the door outward, may be provided, by means of which button said roll can at will be arrested. It will be obvious that owing to this arrangement the floor 20 will be lowered by opening the door 3, when the roll just 55 now mentioned will be arrested by the impressed button. If, however, it is desired to open the front door of the refrigerator without pulling down the floor 20 of the ice-chamber, it is only necessary to disengage the 60 above-stated spring-roll by pulling out the button, so that when the door will be opened the chain is allowed to wind off the roll and when the door is closed to wind up the roll. 65 Before the door could be opened in order to

insert a fresh cake of ice into the refrigerator the drawers 5 5 must be pulled out, so as to clear the space within the food-compartment.

Any suitable means may be provided to hold the door 3 in its open position. This 70 door, as well as the doors 1 of the bottle-compartments, may have glass windows for the convenience of looking into the different compartments without opening the doors. At the top the refrigerator may be provided with 75 a cover suitably hinged to the back wall, and at the bottom the receptacle receiving the water flowing off when the ice melts may be arranged as a drawer, as shown in Figs. 1, 4, and 5. 80

Like in the prior patent, there is a drain-pipe 41 provided, leading from the floor of the ice-chamber into the water-receptacle 42, arranged at the bottom of the refrigerator. This drain-pipe may be fixed to the back wall 85 of the refrigerator and pass through a hole made in the bottom of the ice-chamber, so as to permit this bottom to be moved up and down.

Having thus described the nature of my invention, what I claim as new is—

1. In a refrigerator, the combination with a lower food-compartment, of two bottle-compartments above the latter, an ice-chamber, located between the two bottle-compartments, 90 said ice-chamber having a bottom capable of being lowered down to the bottom of the refrigerator to enable of the insertion of a cake of ice at the bottom of the refrigerator, the food-compartment consisting of two drawers 100 adapted to move laterally opposite each other, and means whereby the floor of the ice-chamber is held in its upmost position, substantially and for the purpose as specified.

2. In a refrigerator, the combination with a lower food-compartment, of two bottle-compartments above the latter, an ice-chamber, between the two bottle-compartments having a floor capable of moving within the refrigerator in a vertical direction, so as to be lowered down to the bottom of the refrigerator, when a fresh cake of ice is to be inserted and raised again so as to lift the cake of ice into the ice-chamber, the food-compartment having two drawers suitably guided upon the 110 bottom of the refrigerator and adapted to move laterally opposite each other, and means whereby the floor of the ice-chamber is held in its upmost position, substantially and for the purpose as specified. 115

3. In a refrigerator, the combination with a lower food-compartment, of two bottle-compartments above the latter, an ice-chamber between the two bottle-compartments having a bottom capable of being moved in vertical 125 direction within the refrigerator, said bottom being suspended from a chain carrying a counterweight at the back of the refrigerator, said counterweight being adapted to always keep the loaded or unloaded bottom in the up- 130

- most position, the food-compartment having two drawers moving laterally opposite each other and guided upon the bottom of the refrigerator, and means for guiding the bottom 5 of the ice-chamber in vertical direction, substantially and for the purpose as specified.
4. In a refrigerator the combination with a box having a double back wall, a free space between the two parts of the back wall, a lower 10 food-compartment consisting of two drawers adapted to be laterally moved in and out, bottle-compartment above the food-compartment, an ice-chamber between the bottle-compartment, said ice-chamber having a bottom 15 balanced by a counterweight arranged within the free space of the double back wall of the refrigerator, said counterweight being suspended from a chain running over a roll mounted upon the inner part of the double 20 wall and attached to the floor of the ice-chamber, and means whereby the floor of the ice-chamber is guided in vertical direction within the refrigerator, substantially and for the purpose as specified.
- 25 5. In a refrigerator, the combination with a food-compartment, of two bottle-compartment above said food-compartment, an ice-chamber between the two bottle-compartment, the ice-chamber having a bottom mov- 30 able in a vertical direction within the refrigerator, bars extending rearward and fixed to the bottom surface of the said floor, these bars being at their inner ends bent upward and connected by a cross-piece, a chain or 35 rope attached to said cross-piece and guided over a roll mounted upon the inner part of the back wall of the refrigerator, said chain carrying a counterweight arranged within the free space of the back wall of the refrig- 40 erator, and means whereby the floor of the ice-chamber is guided in vertical direction within the refrigerator, substantially and for the purpose as specified.
6. In a refrigerator, the combination with a food-compartment, of two bottle-compartment above the latter, an ice-chamber between the two bottle-compartment, the ice-chamber having a bottom movable in vertical directions within the refrigerator, a counter- 45 weight carried by a chain attached to this movable floor, a second chain attached to the
- bottom surface of the said floor and extending downward, said second chain being guided over vertical and horizontal rolls fixed to the bottom surface of the floor of the refrigerator, 55 and attached to the front door thereof, substantially and for the purpose as specified.
7. In a refrigerator, the combination with a food-compartment, of two bottle-compartment above said food-compartment, an ice- 60 chamber between the two bottle-compartment, the ice-chamber having a bottom movable in a vertical direction within the refrigerator, bores arranged in the top part of the front wall of the refrigerator, tubes guided 65 in said bores and tubes fixed to the front part of the floor of the ice-chamber, these tubes being adapted to telescope in each other and the said bores of the front wall, and means whereby these tubes are prevented from fall- 70 ing out from each other and the bores of the front wall of the refrigerator, substantially and for the purpose as specified.
8. In a refrigerator, the combination with the food-compartment, of two bottle-compartment above the latter, an ice-chamber between the two bottle-compartment, the ice-chamber having a bottom movable in vertical direction within the refrigerator, a counter- 75 weight at the back of the refrigerator carry- 80 ing the floor of the ice-chamber by means of a chain, a second chain attached to the bottom surface of this movable floor and extending downward, said chain being guided through the bottom of the refrigerator and 85 over rolls attached to the outside thereof, a roll fixed to the front door of the refrigerator, a spring tending to turn this roll always in a certain direction, so as to wind up the said downward-extending chain, a button pro- 90 jecting outward from the front wall and adapted to be impressed so as to arrest the spring-roll, substantially and for the purpose as specified.

In witness whereof I have hereunto signed 95 my name in the presence of two subscribing witnesses.

LOUIS PEROTTI.
